UNITED STATES PATENT OFFICE

167,321

LADY'S STOCKING

Richard E. Schletter, Cheltenham Township,
Montgomery County, Pa.

Application February 27, 1952, Serial No. 18,677

Term of patent 14 years

(Cl. D47—7)

To all whom it may concern:

Be it known that I, Richard E. Schletter, a citizen of the United States and a resident of Cheltenham Township, county of Montgomery, State of Pennsylvania, have invented a new, original, and ornamental Design for a Lady's Stocking, of which the following is a specification, reference being had to the accompanying drawing, forming part thereof.

In the drawing—

I claim:

The ornamental design for a lady's stocking, as shown.

RICHARD E. SCHLETTER.
